US00D987458S

(12) **United States Design Patent** (10) **Patent No.:** **US D987,458 S**
(45) **Date of Patent:** **** May 30, 2023**

(54) **GAS ANALYZER**

(71) **Applicant:** **YOKOGAWA ELECTRIC CORPORATION**, Musashino (JP)

(72) **Inventors:** **Jun Kobayashi**, Musashino (JP); **Norihiro Tadata**, Musashino (JP)

(73) **Assignee:** **YOKOGAWA ELECTRIC CORPORATION**, Tokyo (JP)

(**) **Term:** **15 Years**

(21) **Appl. No.:** **29/852,640**

(22) **Filed:** **Sep. 8, 2022**

Related U.S. Application Data

(62) Division of application No. 35/512,284, filed on Jan. 25, 2021 (U.S. filing date under 35 U.S.C. 384), and

(57) **CLAIM**

The ornamental design for a gas analyzer, as shown and described.

DESCRIPTION

FIG. 1 is a perspective view of a gas analyzer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the gas analyzer which form no part of the claimed design.

The dot-dash broken lines illustrate boundaries which form no part of the claimed design.

1 Claim, 7 Drawing Sheets

Related U.S. Application Data

having an international filing date of Jan. 25, 2021,
now Pat. No. Des. 974,203.
